UNITED STATES PATENT OFFICE

120,676

DESIGN FOR A COMBINED LIGHTER AND ASH TRAY

Ida Munzer, Chicago, Ill.

Application December 29, 1938, Serial No. 82,045

Term of patent 3½ years

To all whom it may concern:

Be it known that I, Ida Munzer, a citizen of the United States, residing at Chicago, in the county of Cook and State of Illinois, have invented a new, original, and ornamental Design for a Combined Lighter and Ash Tray, of which the following is a specification, reference being had to the accompanying drawing, forming part thereof.

I claim:

The ornamental design for a combined lighter and ash tray, as shown.

IDA MUNZER.
